UNITED STATES PATENT OFFICE.

WALTER J. TURNBULL, DECEASED, BY JOSEPH T. SULLIVAN AND EMILY D. TURNBULL,
EXECUTORS, OF NEW ORLEANS, LOUISIANA.

CONVEYER.

1,112,947.

Specification of Letters Patent.

Patented Oct. 6, 1914.

Original application filed November 12, 1913, Serial No. 800,491. Divided and this application filed March 18, 1914. Serial No. 825,533.

To all whom it may concern:

Be it known that we, JOSEPH T. SULLIVAN and EMILY DELANEY TURNBULL, citizens of the United States, and residents of 5 New Orleans, in the parish of Orleans and State of Louisiana, have been appointed executors of the estate of WALTER J. TURNBULL, deceased, who during his lifetime invented certain new and useful Improvements 10 in Conveyers, of which the following is a specification.

This invention relates to improvements in devices for conveying merchandise, as in the operation of unloading vessels, and it consists 15 in the combinations, constructions, and arrangements herein described and claimed.

The present application is a division of a prior application, Serial No. 800,491, filed Nov. 12, 1913.

20 An object of this invention is to provide a device by means of which a vessel or other similar carrier may be unloaded in a minimum time and at a minimum cost.

A further object of the invention is to 25 provide a movable conveyer which may be elevated or lowered to accommodate the heights of different vessels.

A further object of the invention is to 30 provide a device of the type described comprising an endless conveyer which may be run at any suitable speed, and which is adjustable while running so that as the cargo is lowered the device may be lowered in accordance therewith, thereby providing for a 35 practically continuous discharge of the cargo.

Other objects and advantages will appear in the following specification and the novel features of the device will be particularly pointed out in the appended claims.

40 The invention is illustrated in the accompanying drawings forming part of this application in which—

Figure 1 is a side view of the device in its operative position, the wharf being 45 shown in section, Fig. 2 is a plan view of the device, Fig. 3 is a bottom view of one of the members which form the endless conveyer, Fig. 4 is a section along the line 4—4 of Fig. 3, Fig. 5 is an enlarged side view of a portion of the operating mechanism of the conveyer, Fig. 6 is an enlarged plan view of the upper portion of the conveyer mechanism, and Fig. 7 is an enlarged sectional view on the line 7—7 of Fig. 6.

In carrying out the invention any suitable 55 wharf is made use of, such as that shown at 1 in Figs. 1 and 2. The wharf is supported upon the usual piles 3, certain of these piles being extended to form supporting posts. As will be seen from Fig. 2 60 the wharf has an inwardly extending cut-away portion 4 between opposed posts 3, and the conveyer is designed to be suspended in this cut-away portion in the manner hereinafter described. 65

The conveyer proper consists of a pair of side members such as those shown at 5 in Fig. 7. It will be seen from this figure that these side members bear at their upper parts U-shaped angle irons 6, which form 70 runways for the movable parts of the conveyer. Lower L-shaped angle irons 7 are secured to the side members 5, and form supports for the return portion of the endless conveyer. 75

The endless conveyer is made up of a series of units. These are best shown in Figs. 3 and 4. It will be seen from these figures that each unit consists of a plate 8 having a flat surface with laterally extending flanges 8^a at the sides. At the ends of the plate 8 are integral end members 8^b having lugs or ears 8^c, provided with openings 8^d. The openings in the opposed end members 8^b are in alinement, and a shaft 9 is 85 passed through the alined openings and bears on its outer ends wheels or rollers 10, like those shown in Figs. 5 and 7. As will be seen from Fig. 5 the extension or ear 8^e of one unit overlaps the extension of the adjacent unit and the rod 9 is common to both of these units at this point. This provides in reality a series of long flat and relatively narrow links. On the upper side of the conveyer the links form a practically continuous 90 platform, the short space 11 between the links being practically negligible as far as making a continuous surface is concerned.

In Figs. 5 and 6 is shown the means by which the conveyer is operated. This comprises a motor M whose shaft 12 bears a worm 13. The latter meshes with a worm wheel 14 (see Fig. 6) on a shaft 15. The latter extends through the side members 5 and bears at one end a beveled gear 16, and at the other end the sprockets 17. A drum 18 is also mounted on the shaft 15. The gear 16 is designed to be engaged by a bevel

eled gear 19, which is slidably mounted on a shaft 20. It is held normally out of engagement with the gear 18 by means of a spring 21 (see Fig. 6) but may be brought 5 into engagement with the gear by means of a wedge-shaped yoke 22, which straddles the shaft 20, and which has a handle or shank 23 extending to the opposite side of the machine. The shaft 20 bears a worm 24, which 10 engages a worm wheel 25 on a shaft 26. The latter bears winding drums 27.

As will be seen from Figs. 1 and 2 a bar 28 is disposed underneath the conveyer near the lower end thereof. This bar is connected 15 with the side members 5 by means of inclined braces 29. Cables 30 are secured to the bar 28, pass upwardly, and around pulleys 31, which are secured to the posts on opposite sides of the conveyer. Counter-weights 32 20 are carried by the cables 30. Cables 33 are also secured to the cross member 28 and pass upwardly and over pulleys 34 on the front supporting post or piles 3, thence rearwardly over pulleys 35 on the rear piles or 25 supporting posts, thence downwardly over pulleys 36 on the side members 5, and thence to the winding drums 27 on either side of the conveyer.

From the foregoing description of the various parts of the device the operation thereof may be readily understood.

When it is desired to unload a vessel such as that shown at 37 in Fig. 1, the operator sets the starting lever 38 (see Fig. 6) in a 35 position to start the motor M. The revolution of the latter causes the turning of the gear 16. If now the handle 23 is pushed forwardly so as to bring the wedge-shaped yoke in between the gear 19 and the hanger 39 the 40 gear will be forced into mesh with the gear 16. This will cause the revolution of the shaft 20 and the winding or unwinding of the cables 33 in accordance with the direction of rotation of the motor, that is to say, 45 the outer end of the device can be either raised or lowered so as to accommodate it to the height of the vessel. As soon as the desired height is attained the handle 23 is withdrawn and the spring 21 will force the 50 gear 19 out of mesh with the gear 16. The counterbalancing weights 32 will hold the conveyer at the desired height. The motor may now be speeded up to the required speed for operating the endless conveyer.

55 It will be seen from Fig. 6 that the sprocket wheels are arranged to receive the rollers 10, so that when the shaft 15 is revolving the endless conveyer will be operated so as to cause a movement thereof in the 60 direction shown by the arrows in Fig. 1. Any merchandise which is placed on the conveyer from the deck or unloading platform 40 (see Fig. 1) will be transported by means of the movement of the conveyer onto the 65 dock or warehouse floor, where it may be re-

ceiyed and removed by any suitable apparatus.

One advantage of a device of this kind is that it may be raised or lowered to accommodate the heights of the discharging decks 70 of different vessels or in accordance with the ebb and flow of the tide in seaports. The device requires no cover and does not in any way obstruct the stage, planks, derricks, etc., on vessels, as there are no fixtures other than 75 the supporting posts 3 above the wharf level. One operator at the controller has perfect control of the conveyer.

What is claimed is:

1. In an unloading device, an endless platform comprised of a series of units pivotally connected together, each of said units being provided with rollers, sprocket wheels carried by said conveyer at one end thereof and arranged to receive said rollers, a drive shaft 80 for supporting said sprockets, means for actuating said drive shaft, and means operated by said drive shaft for raising or lowering the opposite end of the conveyer.

2. In an unloading apparatus, an endless conveyer comprising a series of units pivotally connected together, a drive shaft carried by said conveyer at one end thereof, sprocket wheels carried by said shaft and arranged to receive portions of said pivoted 95 units for moving the latter, means for actuating said drive shaft, a gear carried by said drive shaft, an auxiliary gear normally out of engagement with said first named gear, means for bringing said auxiliary gear into engagement with said first named gear, an auxiliary shaft, a pair of winding drums carried by said auxiliary shaft, and means operated through the movement of said auxiliary gear for driving said winding 100 drums.

3. In an unloading apparatus, an endless conveyer comprising a series of units pivotally connected together, a drive shaft carried by said conveyer at one end thereof, sprocket wheels carried by said shaft and arranged to receive portions of said pivoted units for moving the latter, means for actuating said drive shaft, a gear carried by said drive shaft, an auxiliary gear normally out of engagement with said first named gear, means for bringing said auxiliary gear into engagement with said first named gear, an auxiliary shaft, a pair of winding drums carried by said auxiliary shaft, means operated through the movement of said auxiliary gear for driving said winding 115 drums, and cables carried by said winding drums and extending toward and fastened to the opposite end of said conveyer for raising or 120 lowering the conveyer.

4. In an unloading apparatus, an endless conveyer comprising a series of units pivotally connected together, a drive shaft carried by said conveyer at one end thereof, 130

sprocket wheels carried by said shaft and arranged to receive portions of said pivoted units for moving the latter, means for actuating the drive shaft, a gear carried by said drive shaft, an auxiliary gear normally out of engagement with said first named gear, means for bringing said auxiliary gear into engagement with said first named gear, an auxiliary shaft, a pair of winding drums carried by said auxiliary shaft, means operated through the movement of said auxiliary gear for driving said winding drums,

cables carried by said winding drums and extending toward and fastened to the opposite end of said conveyer for raising or lowering the conveyer, and counterweights secured to the conveyer for holding the latter in its adjusted position.
